UNITED STATES PATENT OFFICE.

JOHN DE BUTTS, OF CENTREVILLE, MARYLAND.

CORN-PLANTER.

SPECIFICATION forming part of Letters Patent No. 378,164, dated February 21, 1888.

Application filed November 25, 1887. Serial No. 256,162. (No model.)

To all whom it may concern:

Be it known that I, JOHN DE BUTTS, a citizen of the United States, residing at Centreville, in the county of Queen Anne and State 5 of Maryland, have invented certain new and useful Improvements in Corn-Planters; and I do hereby declare the following to be a full, clear, and exact description of the invention, such as will enable others skilled in the art to 10 which it appertains to make and use the same.

This invention is an improvement on my Patent No. 307,183, dated October 28, 1884, and has for its object, chiefly, to prevent the seed-slide from being withdrawn too soon or jostled 15 out of its place. To effect this object I employ devices for automatically locking and unlocking the shaft which operates said slide and arrange these so that it may be caused to remain stationary, except when the slide ought 20 to be moved in or out. I also provide for more firmly supporting said shaft and its attachments than in the patent aforesaid.

In the accompanying drawings, Figure 1 represents a plan view of a corn-planter embodying my invention. Fig. 2 represents a 25 detail view in side elevation, enlarged, of the slide-operating shaft and the devices for automatically locking and unlocking it, with the supports therefor. Fig. 3 represents a detail 30 perspective view, also enlarged, of the pinion carried by said shaft, the locking devices therefor, and the segment-carrying wheel, with one of the flanges thereon in the act of holding said devices out of locking position. Figs. 4, 35 5, and 6 are additional detail views.

A designates the axle of the corn-planter, to which is attached the main frame B, having a supplemental or seed frame, C, hinged to its forward end. To this latter frame the pole D 40 is attached, and said frame is supported at each side by shoes E, above which the seed-boxes F are arranged.

G designates the seed-slide, which reciprocates transversely of the machine, its ends entering said seed-boxes and alternately covering and uncovering their outlets after the usual manner. This slide is operated by a short lever, H, which is pivoted at the forward end to said frame C and attached near its middle to 45 said slide. The other end of said lever is attached to a transversely-operating pitman, I, which receives motion from a longitudinal

shaft, J, mounted in bearings j j, and provided with a crank-arm, K, and wrist-pin k, to which the outer end of said pitman is 55 loosely secured. The bearings j j are supported by a plate or bar, L, which is arranged longitudinally of the machine, and supports also the bearings l l of the shaft l of a gear-wheel, M, turning with said shaft. In my 60 former patent aforesaid this bar L had its forward end attached to a rigid supplemental bar; but for greater strength and simplicity I now extend the said plate L to the front or supplemental frame, C, and pivot its forward 65 end thereon. Said forward end is hinged to the body of the plate or bar to rise and fall with said frame. The rear end of said bar or plate L is free to move horizontally for a short distance in a guideway, O, attached to the under side of axle A, and is provided with a vertical shifting lever, P, which is pivoted to said axle. This lever works above its pivotal point in a slotted piece, Q, which has an enlargement of its slot at its inner end, q, forming a shoulder for engaging and locking said lever at that point. 75

R R' designate the transporting-wheels of the planter, the latter wheel being also the driving-wheel of the seed-dropping apparatus. 80 To effect this, the said wheel R' has attached to its side or formed therewith a gear-wheel, S, which meshes with the wheel M aforesaid, when the latter is thrown into its outermost position, by turning the outer end of lever P 85 inward, as aforesaid. The forward face of said wheel M is provided at intervals with series of screw-holes m, for the attachment of segments T, one segment to each series. These segments are internally toothed and provided 90 with screws t, which pass through holes in them and enter the said screw-tapped holes or recesses m. On the rear end of shaft J is fixed a pinion, U, which meshes with said segments. The wheel M is preferably adapted to receive 95 four of these segments, and all of these may be used together, or any less number, as stated in my patent aforesaid. As each of these segments comes in contact with said pinion and turns it, the seed-slide G is caused to reciprocate by the action of shaft J, pin k, pitman I, and lever H. To guard against improper motion of said slide, I provide the pinion U with 100 recesses u in its front face, and arrange a pin,

v, on a fixed spring, V, so that the action of the latter will force said spring into one of said recesses whenever it comes opposite the pin. Each of the segments T is provided with 5 a raised flange, W, which comes in contact, as it revolves, with an anti-friction roller, w, also carried by said spring on an arm of the latter, extending outwardly therefrom, and forces back said spring, so as to remove said pin from 10 the recess w. The said flange holds said pin out of engagement with said recess until the segment has ceased to operate on the pinion U and the seed-slide has consequently ended its reciprocating motion. The flange then 15 passes from the roller w, the pin v is forced by spring V into the next recess u, and the shaft J and feed-slide are thereby locked motionless until the next segment and flange come round to repeat the operation.

20 Having thus described my invention, what I claim as new, and desire to secure by Letters Patent, is—

1. In combination with a seed-slide and a shaft for operating the same, a locking device 25 engaging an attachment of said shaft and a rotating toothed segment which meshes with a gear-wheel for driving said shaft, said segment being also provided with a flange for releasing said locking device, substantially as 30 set forth.

2. In combination with a seed-slide and a shaft for operating the same, a locking device engaging an attachment of said shaft, gearing for driving said shaft, and a rotating flange 35 having an inclined face which releases said locking device, substantially as set forth.

3. In combination with a seed-slide and a shaft for operating the same, a locking device engaging an attachment of said shaft, a pinion 40 fixed on said shaft, and a wheel provided with a series of segments which successively engage said pinion, each segment being provided with

a flange for removing said locking device from engagement, for the purpose set forth.

4. In combination with a seed-slide and a 45 shaft for operating the same, a pinion turning with said shaft and having a recess formed therein, a pin arranged to enter said recess, a spring to which said pin is attached and which is provided with an outwardly-extending arm, 50 W', and a rotating segment provided with a flange or projection arranged to act against said arm and withdraw said pin from said pinion, substantially as set forth.

5. A segment having internal teeth and a 55 raised flange, in combination with a wheel to which said segment is attached, a pinion meshing with said segment and having recesses u, a spring provided with a pin for entering said recesses, a roller to be struck by said flange for withdrawing said pin, a shaft turning with said pinion, and a seed-slide operated by said shaft, substantially as set forth.

6. In combination with the frame A and hinged supplemental frame C, the plate or bar 65 L, pivoted at its front end to the latter frame, the shaft turning in bearings thereon, the seed-slides and connections between them and said shaft, the lever for moving said bar laterally, and the operating-gearing which is separated 70 or brought together by this lateral motion, substantially as set forth.

7. The bar L, laterally movable at one end and pivoted at the other, in combination with a hinged frame, C, to which its pivoted end is 75 attached, a shaft mounted in bearings on said bar, the feed-slides, and supporting and driving mechanism, substantially as set forth.

In testimony whereof I affix my signature in presence of two witnesses.

JNO. DE BUTTS.
